UNITED STATES PATENT OFFICE.

GEORGE H. NEVIUS, OF EAST ORANGE, NEW JERSEY, ASSIGNOR TO HUGO SCHNEIDER,
OF TARRYTOWN, NEW YORK.

DESIGN FOR A SURFACE ORNAMENTATION OF AN ARTICLE OF MANUFACTURE.

58,161.

Specification for Design.

Patented June 14, 1921.

Application filed September 22, 1917. Serial No. 192,817. Term of patent 3½ years.

To all whom it may concern:

Be it known that I, GEORGE H. NEVIUS, a citizen of the United States, residing at East Orange, county of Essex, State of New Jersey, have invented a new, original, and ornamental Design for a Surface Ornamentation of an Article of Manufacture Forming a Unit of a Lady's Bureau or Dressing-Table Toilet Set, and of which the following is the specification, reference being had to the accompanying drawing, forming a part thereof.

The figure is a plan view looking at the back of a hand mirror which is an article of manufacture embodying my new design.

My new design is embodied in the various articles constituting a lady's bureau or dressing-table toilet set, being incorporated in the back of each of the following articles, viz: a hair brush, a mirror, a comb, and a nail polisher. It is embodied in the handle of the following articles, viz: a shoe horn, a nail file, a cuticle knife, a corn knife and a button hook. It is embodied in the cover of the following articles, viz: a puff box, a hair receiver and a cream box. It is embodied in the face of the following articles, viz: a pin tray, a brush and comb tray, a pin cushion and a jewel box.

The characteristic of the design resides in the novel and ornamental surface effect which is somewhat difficult to illustrate by means of a drawing because of the manner in which the effect is produced and further because a unique color scheme forms a feature thereof. As illustrated in the accompanying drawing the ornamental surface of the article appears as if it was roughened, whereas as a matter of fact said surface is smooth. The roughened effect is produced by a transparent sheet of composition material, such as celluloid, having semi-transparent or translucent lines formed therein to produce what is termed a "basket-weave" effect, this celluloid sheet over-lying and being united to another composition sheet, preferably of celluloid, having a contrasting color which shows through the transparent or translucent sheet and thus produces the desired effect. As a matter of fact the "basket-weave" effect appears more prominent in the drawing than in the articles themselves.

What I claim is:

The ornamental design for surface ornamentation of an article of manufacture, as shown and described.

GEORGE H. NEVIUS.
